DESIGN FOR A BOTTLE

Brooks Dwight Fuerst, Sylvania, Ohio, assignor to Bowman Dairy Company, Chicago, Ill., a corporation of Illinois

Application August 4, 1948, Serial No. 147,935

Term of patent 14 years

(Cl. D58—8)

To all whom it may concern:

Be it known that I, Brooks Dwight Fuerst, a citizen of the United States, residing at Sylvania, County of Lucas, and State of Ohio, have invented a new, original, and ornamental Design for a Bottle, of which the following is a specification, reference being had to the accompanying drawing, forming a part thereof, in which:

Figure 1 is a side view in elevation of a bottle showing my new design; Fig. 2, a side view in elevation; and Fig. 3, a bottom plan view.

I claim:

The ornamental design for a bottle, as shown.
BROOKS DWIGHT FUERST.
